ENCLOSURES FOR SOUND REPRODUCTION

Robert L. Sewell, Santa Ana, Calif.

Application January 11, 1954, Serial No. 403,242

6 Claims. (Cl. 181—31)

The present invention relates to enclosures for loud speakers used in reproduction of sound.

The arrangements described herein are featured by their simplicity, rigidity and enhanced quality of the reproduced sound, these features being attributed largely to the fact that the enclosure has internally disposed baffle members so arranged that any particular space in the enclosure is defined by walls extending in non-parallel relationship.

A general object of the present invention is to provide an improved enclosure whereby the above indicated results may be achieved.

A specific object of the present invention is to provide a speaker enclosure having chambers therein defined by walls extending in non-parallel relationship.

Another specific object of the present invention is to provide an improved enclosure so constructed as to prevent the formation of standing waves to thereby assure substantially no intermodulation distortion or harmonic distortion.

Another specific object of the present invention is to provide an enclosure having substantially only one resonant frequency and which may be enharmonic of the resonant frequency of the loaded cone of the speaker used in conjunction with such enclosure.

Another object of the present invention is to provide improved enclosures which are suitably braced mechanically by the baffle members so as to greatly minimize what is termed in the art as "cabinet breathing," thereby obtaining relatively high efficiency in the conversion of sound transfer, particularly at low frequencies.

Another specific object of the present invention is to provide improved enclosure construction which requires no internal padding, thereby again assuring high, efficient energy transfer.

Another specific object of the present invention is to provide improved enclosure construction involving so-called front radiation only and which, in providing high fidelity sound reproduction, requires no multiple paths which may otherwise cause cancellation and reinforcements as, for example, in arrangements using a back-loaded horn and a so-called base reflex principle.

Another specific object of the present invention is to provide an enclosure reproductive of high fidelity sound, having relatively small physical size and which is relatively inexpensive.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a view showing in perspective a cabinet construction or enclosure embodying features of the present invention.

Figure 2 is a perspective view, as in Figure 1, with some of the external walls of the cabinet shown in Figure 1 re-

2

moved to illustrate the internal arrangement of the baffle members.

Figure 3 is a perspective view of the three baffle members used in the cabinet construction of Figures 1 and 2.

5 Figures 4 and 5 are sectional views taken substantially on the lines 4—4 and 5—5 of Figure 1.

Figure 6 is a perspective view similar to the cabinet illustrated in Figure 2, but a modified arrangement which, instead of using three baffle members, uses only two baffle members.

10 Figure 7 is a sectional view taken substantially on the line 7—7 of Figure 6.

Figure 8 is a view partly in elevation and partly in section, looking down from the top of another modified cabinet construction which, in this instance, is a corner cabinet.

Figure 9 is a view taken generally on the line 9—9 of Figure 8.

20 The enclosure or cabinet in the first modification illustrated in Figures 1—5 comprises a six-sided rectangular box having three baffle members of unique construction, which are uniquely disposed internally of the rectangular box to define a plurality of chambers, such chambers being defined by non-parallel walls. The box 10 includes the six walls 12, 13, 14, 15, 16 and 17 and the baffle members disposed therein have the reference numerals 18, 19 and 20.

25 While the center baffle member 19, which is generally rectangular as shown in Figure 3, is preferred for mechanical rigidity to prevent cabinet breathing, the same is preferably used but is not considered essential for achieving more particular concepts of the present invention, as will be more clear from a comparison of the structures illustrated on the one hand in Figure 1 and on the other hand in Figure 6.

30 The use of the triangular baffle member 18 is considered important and in the first two modifications illustrated herein, i. e., in Figures 1 and 6, the apex 18A of the triangular baffle member 18 and the apex 20A of the triangular baffle member 20 are disposed in corners of the box 10 which lie at the ends of a diagonal of a particular internal face of the rectangular box or enclosure, while the base 18B and the base 20B of the triangular baffle members 18 and 20, respectively, contact each 35 other on a line corresponding to a diagonal of a face which is opposite to and extends parallel to the aforementioned internal face. Thus, as shown in Figure 1, the apex 18A and the apex 20A are disposed in three-sided corners 10A and 10B of the box 10, which corners are at the ends of a diagonal of the internal face of wall 14; and the bases 18B and 20B contact each other on a line which corresponds to the diagonal of the internal face of the wall 12, such walls 12 and 14 being opposite walls extending parallel to each other.

40 45 50 55 The center baffle member 19, when used, extends between the triangular baffle members 18 and 20 and between diagonally opposite two-sided corners 10C and 10D of the box 10. Using this construction, it is seen that the internal space of the rectangular box is divided into

60 a plurality of chambers, each of which is defined by non-parallel walls. The particular face on which a conventional loud speaker of the cone type (as is commonly used in radios and television sets) is mounted, involves to a certain extent a matter of choice and, as shown in Figure 1, such speaker is intended to be mounted in the central portion of the wall 12, i. e., that wall which is

65 contacted internally by the three baffle members 18, 19 and 20 on substantially the same diagonal line. In order to provide clearance for such speakers, the baffle members 18, 19 and 20 are routed out, as shown in Figure 2,

70 to accommodate the rearwardly extending body of the speaker which generally has a cylindrical housing or base

joined to a conical shaped housing. The degree to which the baffle members are routed out is sufficient only to prevent engagement of the body of the speaker with the baffle members. Otherwise, the chambers defined by the baffle members may be in communication with each other at the place where the three baffle members are routed out, as mentioned above.

The arrangements shown in Figure 6 illustrate the conditions wherein the central baffle member 19 is omitted and, in general, corresponding parts in Figures 1 and 6 have identical reference numerals for ease in comparing the disclosed structures.

The speaker may be mounted in the circular apertured portion 12S of the wall 12, as in Figure 1, and in such case, the baffle members 18 and 20 are routed out, as shown in Figure 3, to accommodate the inwardly protruding portion of the speaker. The speaker 30, which is conventional, in such case is provided with a mounting flange 30A having apertured portions through which suitable screws or bolts pass to fasten such speaker to the wall 12. Instead of mounting the speaker on the wall 12, the speaker may be mounted within the centrally apertured portion 14S in the wall 14 and in such case it is not necessary, of course, that any one of the baffle members be routed, since sufficient clearance is available to accommodate the speaker when mounted on the wall 14.

The baffle members may be secured to the walls of the enclosure by screws or nails, in the manner indicated in Figures 4 and 5 and, if desired, suitable resilient material such as strips of hard sponge rubber 32 may be interposed between the baffle members and the wall or, if desired, between the baffle members themselves.

In the third modification illustrated in Figures 8 and 9, the enclosure or cabinet is adapted for placement in the corner of a room and for that reason is provided with a pair of walls 40 and 50 which extend at right angles to each other, such walls 40 and 50 being attached to the front wall 52 and to the top and bottom walls 53 and 54, respectively. In this case, only one triangular baffle member 60, similar either to baffle member 18 or 20, is used. Baffle member 60 has its apex 60A disposed within the three-sided corner 50A of the enclosure 50 and its base 60B abutting the inner surface of the front wall 52 along a line which extends parallel to the planes of the top and bottom walls 53 and 54 and midway between the same. The front wall 52 is circularly apertured to receive and to mount a conventional speaker; and to accommodate such speaker, the triangular baffle plate 60 is routed out at 60C to provide the desired clearance.

In each of the modifications illustrated herein, it is observed that at least one triangular shaped baffle member is used to provide chambers in an enclosure, such chambers being defined by non-parallel walls so as to obtain the above-indicated results.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A speaker enclosure comprising a rectangular box, said box having a first wall and a second wall spaced from but parallel with said first wall, a pair of triangular baffle members disposed within said box dividing the same into a plurality of compartments each defined by non-parallel walls, said triangular baffle members having their

apices disposed in different three-sided corners of said box, said different three-sided corners being defined by said first wall which is common to each of the three-sided corners, the bases of said triangular baffle members intersecting on a line corresponding to the diagonal of said second wall of said box, and said second wall being centrally apertured on said line to define a central apertured portion, and a speaker mounted in said apertured portion.

2. A speaker enclosure comprising a hollow body, said body having an internal space defined by at least one three-sided corner, a triangular-shaped baffle member disposed within said box and having its apex disposed in said corner, and the base of said triangular-shaped baffle member intersecting a wall of said box on a line to provide a plurality of compartments each defined by non-parallel walls, and said wall being centrally apertured on said line to define a central apertured portion, and a speaker mounted in said apertured portion.

20 3. A speaker enclosure comprising three walls defining a three-sided corner, said enclosure having a fourth wall, a triangularly-shaped baffle member disposed within said box having its apex disposed in said three-sided corner and having its base contacting said fourth wall on a straight line to provide a plurality of compartments of non-parallel walls, and said fourth wall being centrally apertured on said line to define a central apertured portion, and a speaker mounted in said apertured portion.

4. A speaker enclosure comprising a box defined by at least four walls, three of said walls defining a three-sided corner, a triangularly-shaped baffle member having its apex disposed in said corner and its base contacting the fourth wall along a line which extends the full length of the fourth wall, and said fourth wall being centrally apertured on said line to define a central apertured portion, and a speaker mounted in said apertured portion.

5. A speaker enclosure comprising a parallelepiped having six walls, a first three-sided corner defined by a first, a second and a third one of said walls, a second three-sided corner defined by said first, a fourth and a fifth one of said walls, a pair of triangularly-shaped baffle members, one of said baffle members having its apex disposed in the first-mentioned corner and the apex of the other baffle member being disposed in the other of said corners, said baffle members both having their bases intersecting on a line which corresponds to a diagonal of the sixth wall of said parallelepiped, said sixth wall being centrally apertured on said line to define a central apertured portion, and a speaker mounted in said apertured portion.

6. A speaker enclosure having five walls, with the planes of two of said walls intersecting at a right angle, said two walls and a third wall defining a three-sided corner, a triangularly-shaped baffle member having its apex disposed in said corner and having its base contacting a fourth wall of said enclosure along a line which extends substantially the full length of said fourth wall to partition said enclosure into a plurality of compartments defined by non-parallel walls said fourth wall being centrally apertured on said line to define a central apertured portion, and a speaker mounted in said apertured portion.
